COMBINED CALENDAR CLOCK AND RADIO CABINET

John W. Mason, Detroit, Mich.

Application April 29, 1955, Serial No. 35,743

Term of patent 14 years

(Cl. D56—4)

Fig. 1.

Fig. 2.

Fig. 3.

Fig. 1 is a front perspective view of a combined calendar clock and radio cabinet, showing my new design; Fig. 2 is a sectional view thereof along line 2—2 of Fig. 1; and

Fig. 3 is a fragmentary sectional view along line 3—3 of Fig. 1.

The dominant features of my new design reside in the portions thereof shown by full lines of the drawing.

I claim:

The ornamental design for a combined calendar clock and radio cabinet, as shown and described.
